UNITED STATES PATENT OFFICE.

JOHN K. WILDER, OF MONROE, MICHIGAN.

FODDER-CUTTER.

No. 826,459.

Specification of Letters Patent.

Patented July 17, 1906.

Application filed June 20, 1903. Serial No. 162,311.

To all whom it may concern:

Be it known that I, JOHN K. WILDER, a citizen of the United States, residing at Monroe, in the county of Monroe and State of Michigan, have invented certain new and useful Improvements in Fodder-Cutters, of which the following is a specification, reference being had therein to the accompanying drawings.

10 The invention relates generally to fodder-cutters, and has particular reference to a combined cutter and blower or pneumatic conveyer, the latter being adapted to receive the cut material and to elevate the same to a 15 silo or other suitable receptacle.

The invention consists in the novel and simple construction of a fodder-cutter and in the peculiar arrangement and combination of its various parts, as will be fully hereinafter 20 set forth, and shown in the drawings, in which—

Figure 1 is a side elevation of a machine embodying my invention. Fig. 2 is a plan view thereof, the fan-casing being shown in 25 section to illustrate its interior. Fig. 3 is a perspective view of the fan, the latter being shown partly in section; and Figs. 4 and 5 are views in elevation of the discharge-section of the fan-casing, showing the delivery-pipe in different 30 positions in relation thereto. Fig. 6 is a side elevation of the fan-disk. Fig. 7 is a perspective view of one of the fan-plates. Fig. 8 is a section taken on the line 8 8 of Fig. 1, showing a trough and a cutter for the material adjacent to the blade. Fig. 9 is a perspective view of the cutter-plate and one of the blades.

In the drawings thus briefly described, A represents a main supporting-frame, and B is 40 the shaft journaled transversely thereof in suitable bearings C. The shaft at one end projects beyond its bearing and carries thereon a band-pulley D, while mounted centrally upon the shaft within the main supporting-frame is a fan-casing E. This casing as shown 45 is substantially cylindrical, is provided with the usual air-inlet openings a at each side, and carries suitable bearings F, through which the shaft extends, the fan-casing being loosely 50 sleeved upon the shaft and adapted to be adjusted into different positions, as will be hereinafter set forth.

G represents a discharge-section for the fan-case, extending upwardly from the periphery thereof and carrying near its top an 55 annular flange b. Mounted upon the dis-

charge-section and resting against the flange b as its base is a delivery-pipe I, the free or discharge end of which is adapted in the usual manner to be loosely secured to the silo or receptacle that is to be filled.

For the purpose of varying the angle of inclination of the delivery-pipe, which is desirable for well-known reasons, I provide means for effecting the rotary adjustment of 65 the fan-case about the drive-shaft upon which it is suspended. These means preferably consist, as shown, of a rod d, journaled in suitable bearings e on the base of the main frame, a worm f on the rod, and a rack g upon 70 the periphery of the casing above the worm, the parts engaging as shown. To produce the desired adjustment, the rod d is rotated by means of a suitable handle or crank h in a direction to throw the casing either into a 75 forward or rearward position, as desired.

The fan for the casing I have shown in the form of a disk-shaped body J, reference being had particularly to Fig. 3, the peripheral portion of which is fashioned to 80 form abutments K, extending in the plane of the disk and acting as backings for the fan-blades L. The portion of the disk periphery immediately in advance of the abutments is cut away, as indicated at M, so that the maximum portion of a fan-blade will be exposed. Also a slot j is preferably formed in the disk intermediate the portions K and M to receive the lower end of the blade, as plainly 85 indicated in the figure referred to.

Laterally-projecting flanges O, having inwardly-projecting upper ends o, extend from the abutments, preferably from each side thereof, and to these flanges the blades L are 90 rigidly secured by suitable bolts k.

It will be obvious from the construction of the fan that the same, with the abutments and flanges, may be cast in a single piece, which materially reduces the cost of production. Furthermore, the fan-blades being inserted 100 within the peripheral portion of the disk and backed by integral portions thereof a rigid and durable structure is produced and one in which there is but little liability of breakage.

To the fan wheel or disk just described are 105 connected the cutter-blades P. The connections may, if desired, be of the same construction as set forth in Patent No. 529,768, issued to me November 27, 1894. As this feature of the fodder-cutter constitutes no part of the 110 present invention, no further description will be necessary.

The disk is sleeved upon the shaft B within the fan-casing and is rigidly held in place by suitable bolts *l*, extending through the laterally-projecting hubs *m* upon the disk.

5 In the operation of the machine it is frequently necessary to cleanse the delivery-pipe, and to permit of this being readily accomplished I arrange the pipe upon the fan-casing in such manner that it may be readily shifted out of alignment with the discharge-opening, so that the material in the pipe may drop through onto the ground. In the drawings I have shown the delivery-pipe resting at its lower end upon the collar *b* of the discharge-section. A bell-crank lever *Q* forms an operative connection between the pipe and casing and serves as a means for shifting the pipe. This lever, as shown, is fulcrumed at a point *a'* to the discharge-section and has its short 20 arm *b'* pivoted at *c'* to the lower edge of the pipe. When it is desired to move the delivery-pipe, the operator by actuating the lever shifts the pipe upwardly and laterally until it assumes the position indicated in dotted lines 25 in Fig. 4.

What I claim as my invention is—

1. In a fodder-cutter, the combination of a fan-casing, and a fan rotatable therein, comprising a disk having portions of its periphery slightly reduced to form abutments and having integral laterally-extended flanges at said reduced portions, and a series of fan-blades having interlocking slotted engagement with the disk immediately adjacent the abutments by which latter they are backed.

2. In a fodder-cutter, the combination of a fan-casing and a fan rotatable therein, comprising a disk having portions of its periphery slightly reduced to form abutments, and a series of fan-blades having interlocking slotted engagement with the disk at said reduced portions and adjacent the abutments, by which latter they are backed. 40

3. In a fodder-cutter, the combination of a fan-casing and a fan rotatable therein, comprising a disk having portions of its periphery slightly reduced to form abutments and having laterally-extended flanges at said reduced portion, a series of fan-blades having interlocking slotted engagement with the disk immediately adjacent the abutments by which latter they are backed, and means for securing said blades to said flanges. 45

4. In a fodder-cutter, the combination with a fan-casing, and a fan rotatable therein, comprising a disk having portions of its periphery slightly reduced to form abutments, and having laterally-extended flanges with inwardly-projecting upper ends, said flanges being arranged adjacent said reduced portions, and a series of fan-blades having slotted engagement with said disk adjacent the abutments, by which latter they are backed. 50

In testimony whereof I affix my signature in presence of two witnesses.

JOHN K. WILDER.
